W. P. WILLSON

REFRIGERATOR

Filed Aug. 20, 1923

William P. Willson

INVENTOR.

BY

Chappell & Earl
ATTORNEYS

UNITED STATES PATENT OFFICE.

WILLIAM P. WILLSON, OF ARLINGTON, VERMONT, ASSIGNOR TO WILLIAM E. KIDDER, OF KALAMAZOO, MICHIGAN.

REFRIGERATOR.

Application filed August 20, 1923. Serial No. 658,475.

To all whom it may concern:

Be it known that I, WILLIAM P. WILLSON, a citizen of the United States, residing at Arlington, county of Bennington, State of Vermont, have invented certain new and useful Improvements in Refrigerators, of which the following is a specification.

This invention relates to improvements in refrigerators.

10 The main objects of this invention are:

First, to provide an improved refrigerator which is highly efficient in the preservation of food, the air in the provision chamber being kept dry and at satisfactory temperature for the purpose.

Second, to provide an improved refrigerator which is very economical in the consumption of the refrigerant.

Third, to provide an improved refrigerator having these advantages which is very easily supplied with the refrigerant.

Further objects, and objects relating to structural details, will definitely appear from the detailed description to follow.

25 I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a front elevation of my improved refrigerator.

35 Fig. II is a vertical central section through my improved refrigerator, parts being shown in full lines for convenience in illustration.

Fig. III is a horizontal section on a line corresponding to line 3—3 of Fig. II.

Fig. IV is a detail vertical section on a line corresponding to line 4—4 of Fig. II.

In the drawing similar reference characters refer to similar parts throughout the several views, and the sectional views are taken looking in the direction of the little arrows at the ends of the section lines.

50 Referring to the drawing, I provide a suitable casing which, in the structure illustrated, comprises the outer wall 1 prefer-

ably of wood, an inner wall or lining of metal 2 and an insulating filling 3 between them. The casing is provided with provision chamber doors 4 at the front and a refrigerant chamber door 5 at the top.

55 At the bottom of the casing is a pan 6 having a drain opening 7.

The refrigerant chamber comprises a bottom portion 8 and a vertical portion 9, the lining or inner wall 3 of the casing constituting the outer walls of this refrigerant chamber. The inner wall 3 has a pan-like portion 10 at the bottom disposed within the pan 6, being supported therein by the cross pieces 11 formed of sheet metal and 60 having offsets 12 therein supporting the refrigerant chamber with its bottom in a spaced relation to the bottom of the pan 6. I have not shown the seams of these walls as the structural details thereof form no 65 part of this invention.

70 The inner wall 13 of the refrigerant chamber is inclined so that the refrigerant chamber expands downwardly. This prevents the refrigerant, which is preferably chipped ice with a suitable chemical, from becoming clogged and should it become frozen to the walls, it is readily detached and forced downwardly by a tamper bar or the like.

75 The refrigerant chamber is adapted to 80 contain a liquid and has a drain pipe 14 provided with a valve 15 and a liquid level pipe 16 which projects upwardly within the refrigerant chamber, its inner end being preferably curved to prevent clogging and 85 also providing a trap, preventing the entrance of air when the liquid level reaches the end of the pipe 16.

90 The provision chamber 17 is provided with a vertical wall 18, spaced from the inner wall 13, and a bottom wall 19 spaced from the top wall 20 of the horizontal portion of the bottom portion of the refrigerant chamber, thereby providing an air passage 21 which is open at 22 to the top of the provision chamber and at 23 to the bottom thereof.

95 The walls 18 and 19 are imperforate so that the air must circulate through this passage 21 from top to bottom and in such cir- 100

culation comes in contact with the wall 13 of the refrigerant chamber.

A wall 13' extends forwardly from the upper end of the wall 13 providing a hopper 5 facilitating the filling of the refrigerant chamber. When the door or cover 5 is opened the refrigerant may be dumped into the hopper and pushed therefrom into the refrigerant chamber.

10 An opening 25 connects the air passage with the bottom pan 6, so that should any moisture accumulate in the passage, it will pass into the pan. However, when the refrigerator is kept properly supplied with 15 the refrigerant, there is little or no moisture to drain away as it will collect in the form of frost on the walls 13 and 20.

My improved refrigerator is very efficient, it being possible to maintain the desired temperatures for food preservation, and further, the temperature in the provision chamber is quite uniform, the air being effectively circulated from top to bottom thereof and being brought into contact with the refrigerant chamber walls is quickly cooled and any excess moisture therein is deposited in the form of frost on the walls of the refrigerant chamber.

I have not attempted to illustrate and describe certain modifications and adaptations which I contemplate as I believe the disclosure made will enable those skilled in the art to which my invention relates to embody or adapt the same as may be desired.

35 Having thus described my invention, what I claim as new and desire to secure by Letters Patent, is:—

1. A refrigerator comprising a casing provided with a provision chamber door at the front and a refrigerant chamber door at the top, a bottom pan disposed in the bottom of said casing and provided with a drain opening, a refrigerant chamber adapted to hold a liquid and comprising a horizontal bottom portion disposed within said bottom pan and a vertical portion disposed at the rear of said casing, a wall extending forwardly from the upper end of said refrigerant chamber inner wall and constituting a hopper 5 facilitating the charging of said refrigerant chamber, and a provision chamber comprising a rear wall spaced from said inner wall of said refrigerant chamber and a bottom wall spaced from the top wall of the horizontal portion of said refrigerant chamber providing an air circulating passage between such refrigerant chamber walls and provision chamber walls, the upper end of said rear wall being spaced from the said hopper bottom wall and the front end of said bottom wall being spaced from the front wall of the casing providing circulating openings, said circulating passage being otherwise closed to said provision chamber,

there being a drain opening from said circulating passage to said bottom pan, said refrigerant chamber being provided with a liquid waste pipe having its inlet in spaced relation to the bottom thereof.

2. A refrigerator comprising a casing provided with a provision chamber door at the front and a refrigerant chamber door at the top, a refrigerant chamber comprising a horizontal bottom portion and a vertical portion disposed at the rear of said casing, a wall extending forwardly from the upper end of said refrigerant chamber inner wall and constituting a hopper facilitating the charging of said refrigerant chamber, and a provision chamber comprising a rear wall spaced from said inner wall of said refrigerant chamber and a bottom wall spaced from the top wall of the horizontal portion of said refrigerant chamber providing an air circulating passage between such refrigerant chamber walls and provision chamber walls, the upper end of said rear wall being spaced from the said hopper bottom wall and the front end of said bottom wall being spaced from the front wall of the casing providing circulating openings, said circulating passage being otherwise closed to said provision chamber.

3. A refrigerator comprising a casing, a bottom pan disposed in the bottom of said casing and provided with a drain opening, a refrigerant chamber adapted to hold a liquid and comprising a horizontal bottom portion disposed within said bottom pan and a vertical portion, and a provision chamber comprising a vertical wall spaced from a vertical wall of said refrigerant chamber and a horizontal bottom wall spaced from a horizontal wall of said refrigerant chamber providing an air circulating passage between such walls, said passage being open at the top and bottom thereof to said provision chamber but otherwise closed thereto, there being a drain opening from said circulating passage to said bottom pan, said refrigerant chamber being provided with a liquid waste pipe having its inlet in spaced relation to the bottom thereof.

4. A refrigerator comprising a casing, a refrigerant chamber comprising a horizontal bottom portion and a vertical portion, and a provision chamber comprising an imperforate vertical wall spaced from a vertical wall of said refrigerant chamber and an imperforate horizontal bottom wall spaced from a horizontal wall of said refrigerant chamber providing an air circulating passage between such walls, said passage being open at the top and bottom thereof to said provision chamber but otherwise closed thereto.

5. A refrigerator comprising a casing, a refrigerant chamber comprising a horizontal bottom portion and a vertical portion,

- the walls of the vertical portion being disposed so that it expands downwardly, and a provision chamber comprising a vertical wall spaced from a vertical wall of said refrigerant chamber and a horizontal bottom wall spaced from a horizontal wall of said refrigerant chamber providing an air circu- lating passage between such walls, said passage being open at the top and bottom thereof to said provision chamber but otherwise closed thereto.
- 5 In witness whereof, I have hereunto set my hand.

WILLIAM P. WILLSON. [L. S.]
